UNITED STATES PATENT OFFICE

FRED ASHWORTH, OF WENHAM, MASSACHUSETTS, ASSIGNOR TO UNITED SHOE MACHINERY CORPORATION, OF PATERSON, NEW JERSEY, A CORPORATION OF NEW JERSEY

HEEL MACHINE

Application filed September 4, 1923, Serial No. 660,750, and in Canada April 4, 1923.

This invention relates to heel machines and is herein illustrated as embodied in a machine capable of performing automatically in sequence the operations of compressing and breasting a heel.

Letters Patent No. 1,501,171, granted July 15, 1924, upon application of Thomas Lund, discloses and claims broadly a practical machine adapted to perform the above stated operations upon heels, and the present invention may, in certain of its aspects, be regarded as in the nature of an improvement upon and development of the Lund invention. It will be manifest, however, as the present description proceeds, that certain features of the present invention are not limited in their utility to a machine for performing the particular operations named, but are well suited to their own uses in shoe machinery of various types.

One important object of the invention is to increase the certainty, accuracy, smoothness and speed of operation of machines in which blanks such, for example, as heels are fed automatically to one or more positions where operations are performed upon them. In the illustrated machine there is provided a blank feeding mechanism operating to advance a blank in a straight line to a position for the performance of an operation upon the blank and then, by continued movement in the same line, to advance the blank from the operating means to a second position where the blank may either be subjected to another operation or discharged. A pair of endless chains arranged to engage the edges of the blanks frictionally and moving always in the same direction may advantageously be utilized in the blank feeding mechanism and, in the illustrated machine, the construction and arrangement are such that a plurality of heels are fed simultaneously to different positions. Practical experience has shown that feeding mechanism of this nature operates smoothly, rapidly and accurately, by reason of the elimination of the destructive shocks and vibrations which are unavoidable when comparatively heavy reciprocating blank feeding mechanism is employed.

Speed of operation in machines for per-

forming multiple operations upon heels is greatly aided by employing a single blank feeding means for advancing the blanks to the successive operating positions, in accordance with the present invention, and by frictional engagement of the blank feeding means with the blanks, which makes it possible for the same feeding mechanism to feed different blanks simultaneously through different distances when required.

Many other advantageous features and details of the invention will best be understood and appreciated by reading the following description of one successful, practical embodiment thereof in connection with the accompanying drawings, in which

Fig. 1 is a perspective view, from the front, of the principal operating parts of a heel compressing and breasting machine, with portions broken away to reveal parts which would otherwise be hidden;

Fig. 2 is a perspective view of the machine from the rear;

Fig. 3 is a central vertical section on a plane extending from front to rear of the machine;

Fig. 4 is a front elevation with certain parts of the mechanism removed;

Fig. 5 is a perspective view showing principally the breasting mechanism, as seen from the rear;

Fig. 6 shows a detail of an automatic mechanism for stopping the machine under certain conditions;

Fig. 7 is a perspective view of a detail of the breasting mechanism;

Fig. 8 shows a one-way clutch which forms part of the mechanism for transmitting motion to the feed chains;

Fig. 9 shows a detail of the feed chain driving and controlling mechanism;

Fig. 10 is a horizontal section of the breasting knife mounting;

Fig. 11 shows a detail of means for adjusting the position of the breasting knife; and

Fig. 12 shows a detail of the mechanism for positioning a heel with respect to the breasting knife.

Referring now to the drawings which, as previously stated, illustrate a machine for per-

forming the two operations of compressing and breasting upon heel blanks, 20 indicates a conventional type of frame similar to those commonly used for commercial heel compressors. A stationary heel seat forming die 22 is supported in the frame 20, being immovably secured in operative position by a bolt 24.

The heel seat die co-operates with the usual compressing mold, comprising a breast die 26 and side dies 28, carried by a cross head 30 which is mounted to reciprocate vertically on suitable guides in the frame 20. Reciprocation of the cross head is effected by the usual toggle mechanism 32 operated by a connecting rod 34 from the crank shaft 36 which is the main driving shaft of the machine. Further detailed description of this mechanism is unnecessary inasmuch as it is already well known in the art.

In the illustrated machine provision is made for supplying heel blanks automatically to the feeding mechanism as, for example, by conveying them directly from a heel building machine by means of an endless conveyor. This conveying mechanism is more fully illustrated and described in a copending application of the present inventor, Serial No. 537,946 filed Feb. 20, 1922, to which reference may be had for a complete description of its mode of operation. For the purpose of the present disclosure it is sufficient to say that a pair of endless chains 38 carrying a series of heel feeding fingers 40 is advanced intermittently, in timed relation to the operation of the compressor, to deliver heel blanks one at a time from the end of a delivery plate 42. Secured to, and projecting forwardly from, the vertically reciprocating cross head 30 is a support 44 in which is mounted a table 46 which receives the heel blanks from the delivery plate 42.

As clearly shown in Figs. 1 and 3 the table 46 enters a corresponding recess in the top of the support so that the upper surfaces of the table and support are flush with each other. The table 46 is secured to the upper end of a plunger 48 which passes through the support 44, and the lower end of which is arranged to be engaged by an operating device 50, upon the forward end of the ejecting lever 52 which is pivoted at 54 to the cross head 30 and the rear end 56 of which engages and operates the depending stem 58 of the heel ejecting member 60 of the compressing mold. The lever 52 is operated at the proper times by a rod 62 which passes through a stationary friction device 64, in co-operation with the vertical movement of the pivot 54.

The operation is such that, when the cross head 30 is in its uppermost position, the heel receiving table 46 is elevated considerably above the surface of the support 44 and is sufficiently close to the delivery plate 42 to receive a heel therefrom without danger of mis-

placement of the heel. This uppermost position of the cross head, as will be understood, is the position in which a blank is under compression in the compressing mold. When the cross head descends, the compressed blank must be ejected from the mold and an uncompressed blank fed to compressing position. The ejection of the compressed blank is accomplished by the lever 52 elevating the ejecting member 60 in the usual manner.

As the end 56 of the lever 52 rises, the operating device 50, at the opposite end of the lever, descends, allowing the table 46, with the heel blank which has been deposited thereon from the delivery table 42, to descend until the top of the table 46 is flush with the upper surface of the support 44. The heel blank is now in a position from which it may be fed in a single straight line movement to the compressing mold. The mechanism for effecting this feeding movement will now be described.

Arranged at opposite sides of the table 46 and the compressing mold, and extending from the front to the rear of the machine, is a pair of endless feed chains 66. At the front of the machine each of the chains 66 is engaged by a driving sprocket 68 which is secured to a vertical shaft 70. Each shaft 70 is supported in a bearing carried by a housing member 72 which, in turn, is mounted to swing through a limited arc about the axis of a vertical shaft 74 (see Fig. 9). The two housing members 72 are connected to swing simultaneously and equally toward and from each other by segmental gearing 76, one of the housings 72 being provided with a laterally extending arm 78 which is operated at proper times by mechanism which will be described hereinafter.

Each sprocket 68 is geared by a chain 80 to a corresponding sprocket 82 which has rigidly secured to it a gear 84. The two gears 84 are so connected by a pair of gears 86 that they run at equal speeds in opposite directions.

The driving of the gearing 84, 86 and, ultimately, of the feed chains 66, is effected by the following mechanism: A rod 88 (see Fig. 4) is guided for vertical sliding movement in a bearing 90 formed in a stationary bracket 92 secured to the machine frame 20. The upper end of the rod 88 is in the form of an enlarged plunger 94, forming a shoulder 96 arranged to engage and be stopped in its downward movement by the top of the bearing member 90. Rack teeth 98 cut in one side of the plunger 94 engage a spur gear 100 to which is secured a bevel gear 102 meshing with a bevel pinion 104 carried by one member 106 of a one-way clutch. The clutch member 106 has a spring pressed pin 108 projecting from its upper face and arranged to engage a tooth 110 formed on the lower face of a second clutch member 112. The hub of the clutch

member 112 is provided with a notch 114 which is engaged by a lug 116 upon one of the gears 84. Upward movement of the rod 88 and plunger 94 is limited by an adjusting nut 118 threaded upon the lower end of the rod and secured in adjusted position by a lock nut 120.

The operation of the mechanism just described is as follows: When the cross head 30 rises, the plunger 94 is carried upward until the nut 118 on the lower end of the rod 88 engages the lower end of the bearing 90. Any further upward movement of the cross head results in rotation of the gearing 100, 102, 104, and the clutch member 106. This rotation is in the direction in which the clutch is inoperative to transmit power and consequently the feed chains 66 are neither advanced nor retracted. The adjustment of the nut 118, however, determines the point, with relation to the tooth 110, at which the pin 108 shall stop and, therefore, the amount of lost motion between these two elements which will occur before the pin engages the tooth 25 and begins to rotate the clutch member 112 on the next downward stroke of the cross head. It will be understood that this adjustment affords means for varying the distance through which the feed chains 66 shall move 30 each time they are operated.

On the downward stroke of the cross head 30 the plunger 94 descends until the shoulder 96 engages the bearing 90, whereupon the continued downward movement of the cross head causes rotation of the gearing 100, 102, 104 in the direction to cause the pin 108 to engage the tooth 110 and drive the member 112 of the clutch. Through the power transmitting connections already described this causes the inner stretches of the feed chains 66 to be advanced from the front toward the rear of the machine.

The feed chains 66 are designed to engage frictionally the edges of a heel blank which has been deposited upon the table 46, after the table has descended to the position shown in the drawings, and feed the blank from the table 46 to the compressing mold. To this end it is necessary that the feed chains be separated sufficiently to allow the blank to enter between them, without danger of misplacement, when the table descends from blank receiving position; and then move toward each other until they firmly engage the edges of the blank. The arm 78 is connected by a link 122, which passes through the cross head 30, to a lever arm 124 at the back of the machine, the rear end of the link 122 being surrounded by a spring 126 which tends to move the link rearwardly. The lever 124 is fulcrumed on an upright stud 138 secured in a bracket 128 projecting from the rear face of the cross head 30 by a set screw 139, and the inner end of the lever is geared to an arm 130, also fulcrumed in the same bracket. On

the upper side of the lever 124 is a U-shaped member 132 into which are adjustably threaded two set screws 134 the line joining the points of which is slightly eccentric to the axis about which the lever 124 moves. A swinging arm 136 is also pivoted upon the stud 138 and is provided with a depending ear 140, the lower end of which is positioned between the points of the set screw 134. From the foregoing it will be understood that oscillation of the lever 124 will cause the arm 136 to swing about its pivot 138, and that the limits of movement of the said arm may be varied by changing the adjustment of the screws 134.

The outer end of the arm 136 has a bearing 142 for an upright stud 144 upon which is pivoted a swinging fork 146. A set screw 148 is arranged to engage the stud 144 and secure it in the arm 136. An adjustable stop screw 149 is threaded through the fork 146, a lock nut 151 being provided to secure it in adjusted position. The point of the screw 149 bears upon a portion of the arm 136, providing for angular adjustment of the fork 146 relatively to the arm. The fork 146 carries a freely turning, idle sprocket around which the corresponding feed chain 66 passes and the angular adjustment of the fork is for the purpose of tightening the chain. 90 95 98 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360

Movable with the arm 130 is a swinging arm 150 which corresponds to the arm 136 and is provided with an enlarged end 152 in which is secured a stud 154 upon which is pivoted a fork 156 corresponding to the fork 146. The fork 156 is provided with an idle sprocket for the other feed chain 66 and a set screw 158 has a function similar to that of the set screw 148. An adjusting screw 153, threaded through the fork 156 and provided with a lock nut 155, bears against a portion 157 of the arm 150 and provides for tightening the second feed chain 66. By reason of the gearing together of the levers 124 and 130 the arms 136 and 150 are caused to move equally toward and from each other and, by the link connection 122, a corresponding simultaneous movement of the housings 22 is effected. The practical result is that the feed chains 66 are maintained in parallel relation and are moved, at suitable times, toward and from each other to engage and release blanks which are between them.

The mechanism just described is operated in proper time relation to the compressing mechanism by a cam 160, on the crank shaft 120, which engages a roll 162 in one end of a cam lever 164 which is pivoted at 166 to a stationary bracket 168 bolted to the machine frame. The opposite end of the lever 164 is connected by an adjustable link 170 to a horizontal rocker arm 172 secured to the shaft 173 upon which the arm 130 is mounted. The cam 160 is so formed that, as the cross head 130 descends and a blank upon the table 46 is 125 130

deposited between the feed chains 66, the said chains are moved toward each other until they firmly engage the edges of the blank, whereupon the feed chains are moved through a sufficient distance to advance the blank to a position upon the ejector plate 60 of the compressing mold, which ejector is, at this time, in its elevated position. The approaching movement of the feed chains which causes them to engage the blank upon the table 46 also causes them to engage the previously compressed heel which has been ejected from the mold by the plate 60 and transfer it from compressing position to the breasting mechanism which will presently be described. Bars 174 between the two stretches of each of the chains 66 afford rigid supports for said chains against transverse yielding and insure the maintenance of firm engagement between the chains and the blanks. These bars are mounted upon the chain carriers and partake of the movements of approach and separation of the chains. During the next upward stroke of the cross head 30 the feed chains separate, releasing the blanks and, the plate 60 descending, the blank which rests thereon is deposited in the compressing mold where it is compressed in the usual manner.

In order that the blanks shall enter the compressing mold properly it is necessary that they be accurately deposited upon the plate 60. Under certain conditions, when molds are changed for heels of different sizes, breast dies 26 of different thicknesses are used and under these circumstances it is necessary to deposit the heel blank upon the plate 60 with its breast edge in a different position. This is provided for by initially delivering the blank to different positions upon the table 46, such positions being so selected that the movement of the blank effected by the feed chains 66 will be just sufficient to deposit the blank in exactly the right position with respect to the compressing mold. To this end edge guides 176, 178 are provided upon the delivery table 42. An adjustable slide 180, regulated by a screw 182, is provided with an upright pin 184 engaging the rear gage member 176, which is adjustable about a pivot 186. The front gage 178 is similarly adjusted by a screw 188. By appropriate adjustment of the two gages 176, 178 the position in which the blank is deposited upon the table 46 is appropriately determined and by this adjustment, in connection with the feed chain adjustment afforded by the nut 118, the location of the blank with respect to the compressing mold may be controlled with precision.

As has already been indicated, the illustrated machine is arranged to compress heel blanks and then to breast the compressed blanks. The breasting mechanism and its relation to the compressing mechanism will now be described.

55 To the rear portion of the cross head 30 is

secured an upright frame 190 which moves up and down with the cross head. V-shaped surfaces 192, formed on the side members of the frame 190 slide in V grooves 194 in the edges of a knife holder 196. The knife holder 196 has a recess 198 into which enters a projection 200 formed upon a stationary bracket 202 which is bolted to the machine frame 20. The knife holder 196 is thus held stationary while the cross head 30 approaches and recedes from it.

70 A heel breasting knife 204 is secured in the knife holder by draw bolts 206 which pass through bosses 208 formed on the knife holder and are tightened by nuts 210. Each of the bolts 206 has a rectangular head 212 arranged to move in a notch 214 in a wedge block 216 through which the draw bolt passes. The co-operating wedge block 218 has slots 220 through which the draw bolts also pass. 80 A pair of wedge blocks is provided for supporting each edge of the breasting knife and each of the blocks 216 has a shoulder 222 against which an edge of the breasting knife is drawn by the heads of two of the bolts 206.

85 The two pairs of co-operating wedge blocks provide means for regulating the position of the breasting knife in a direction transverse to its cutting edge and, being independently adjustable, they also provide for varying its angular position, in a horizontal sense. Each of the wedges 218 has threaded into its upper end a screw 224, the head of which engages in a slot 226 formed in the front side of the knife holder 196, the screws 224 serving to 90 control the adjustment of the wedges. It will be understood that the adjustment of the wedges is effected with the nuts 210 slackened. The said nuts are then set up, to secure the breasting knife rigidly in its adjusted position. A portion of the knife holder projects forwardly, as shown at 228 and adjustable knife stops 230 are threaded through the projection, the adjustment of the stops being maintained by lock nuts 232. The stops 230 100 determine the vertical position of the breasting knife. Gibs 234 on the face of the knife holder form ways to receive a chip guard 236, which is freely movable vertically in the said ways but is prevented from dropping out by lugs 238 bent from the body portion of the guard and resting upon the upper ends of the gib. The guard is provided with a shield 240 which fits the space between the guard and the breasting knife, preventing chips 110 from being jammed in the said space, and causing the chips to be discharged downwardly in front of the heel support presently to be described.

115 A cylindrical plunger 242, operating through a spring pressed friction sleeve 244, serves as a presser foot to hold a heel in position while it is being breasted. The friction sleeve is mounted in the knife carrier and is, therefore, stationary. A rod 246 extends up- 120 125 130

ward from the plunger 242 and its upper end is engaged by the vertically reciprocating frame 190 to operate the plunger in a manner which will be more fully described herein-after.

After a compressed heel is removed from the compressing mold, it is transferred by the chains 66 to breasting position, where it is deposited upon a heel support 248 mounted upon the cross head 30. The position of the heel with respect to the breasting knife is determined by a fork shaped back gage 250 carried by a supporting member 252 and adjustable forwardly and rearwardly thereof by means of a screw 254 which is threaded into the member 252 and whose head engages a slot in the back gage 250. The supporting member 252 is mounted upon the upper end of a vertically movable plunger 256 having at its lower end a cam roll 258 which rests upon an oscillatory cam 260 carried by an arm 262 secured to the shaft 173. It will be apparent that the rocking of the shaft 173 will cause the cam 260 to oscillate and consequently the supporting member 252 and the back gage 250 to rise and fall. The purpose of this movement of the back gage and its support is to present the back gage in position to locate the heel for the breasting operation and then to lower the back gage sufficiently to permit the breasted heel to be discharged over it.

Inasmuch as the back gage 250 is relatively low and, in order to prevent heels from accidentally passing over it or otherwise failing to be properly located by it, stops 264, are adjustably mounted upon the bars 174 and are so arranged that the rear, curved end of the heel will engage them at, or slightly before, the time when the heel has reached the back gage 250. These stops are of substantial height and are sufficient to prevent the heel from being accidentally carried past breasting position. After the feeding movement of the chains 66 has stopped the chains separate, carrying the stops 264 with them out of engagement with the heel, which is left in very nearly, or exactly, proper position to be breasted.

In order to insure that the heel shall be positioned with the utmost precision a striker 266 is pivoted at 268 and provided with heel breast engaging members 270. The striker is operated at proper times by mechanism which will now be described.

A bracket 272, bolted to the machine frame 20 carries two stationary cams 274 and 276. An arm 278 secured to the striker 266 carries a cam roll 280 arranged to engage the cam 274 and held against the cam by a spring 282. A latch 284 is pivoted at 286 in the cross head 30 and is controlled by a cam roll 288 which engages the cam 276. When the cross head starts to rise the latch is held out of engagement with the arm 278 by the cam 276

until the roll 280 has passed into the low part of the cam 274, permitting the spring 282 to operate the striker 270 gently to engage the breast face of the heel and position it accurately against the back gage 250. The striker 270, being arranged to engage the heel breast at separated points, orients the heel as well as positions it longitudinally. As the cross head rises further the roll 288 passes into the low part of the cam 276 and when finally the roll 280 rides upon the upper rise of the cam 274, the striker 270 is retracted and the latch 284 is hooked over the end of the arm 278, locking the striker in its retracted position where it remains during the breasting operation.

When the cross head descends the striker is held retracted by the latch 284 until the roll 288 reaches the rise on the cam 276, whereupon the striker is unlocked and is operated suddenly by the spring 282, striking the heel a sharp blow and knocking it into the discharge chute 290. At the time when the striker is released by the latch 284 the roll 280 is out of engagement with the cam 274 and its position is such that it moves into the low part of the said cam as the striker operates. In the final portion of the descent of the cross head the roll 280 rides upon the lower rise of the cam 274, again retracting the striker 270 to inoperative position.

In order to control properly the timing of the descent of the back gage 250 and the supporting member 252 a slideable rod 292 is arranged to engage the member 252 and maintain it in elevated position after it has been raised by the cam 260. For the purpose of retracting the rod, to release the member 252 and allow it and the back gage to descend under the influence of the spring 294, a bell crank lever 296 is pivoted at 298 to the frame 190, a vertical arm of the lever engaging the rod 292 and a horizontal arm being drawn upward by a spring 300. A stationary pin 302 projects from the rear face of the knife holder 196 and is arranged to be engaged by the horizontal arm of the bell crank lever when the cross head 30 reaches the upper limit of its movement. This causes the rod 292 to be retracted, permitting the back gage to descend sufficiently to allow the breasted heel to be discharged over it.

In order to prevent damage to the work or breakage of the machine during the progress of the heels therethrough means is provided for automatically stopping the machine in the event of any misplacement of a heel which is likely to occur. If a heel should be in a position between the table 46 and the compressing mold, or between the compressing mold and the breasting mechanism, as the cross head 30 nears the upper limit of its movement there is danger that such a heel will be caught between parts of the machine and destroyed, and a possibility of breaking

some part of the machine. Feelers 304 are, therefore, arranged to engage the top of the cross head, in the feeding path, at these places at the time mentioned and to operate mechanism for stopping the machine if a blank is 5 improperly present. The feelers 304 are mounted on a rocker member 306 arranged to swing about stationary pivots 308 and provided with a lever arm 310 connected to a 10 vertically movable rod 312.

A cam 314 secured to the crank shaft 36 actuates one arm 316 of a bell crank lever, the other arm 318 of which extends forward and carries a block 320 through which the rod 15 312 passes. This arrangement controls a well known form of stopping mechanism, and it is sufficient to explain here that whether or not the machine shall be stopped is dependent upon the amount of relative movement between the rod 312 and the block 320. If this 20 relative movement is sufficient the machine is stopped, otherwise it continues to run without interruption. The cam 314 oscillates the lever 318 once for each cycle of operation of the machine. If a heel blank is in position 25 to engage either of the feelers 304 when the cross head 30 rises the rod 312 will be depressed and the relative movement between it and the block 320 will be sufficient to stop 30 the machine. On the other hand, if no blank is in position to engage either of the feelers the rod 312 will not be depressed and the relative movement referred to will not be sufficient 35 to stop the machine, which will continue to operate in the regular manner.

Novel features of the heel breasting mechanism described, but not claimed, herein are claimed in my copending application Ser. No. 481,836 filed Sept. 15, 1930 as a division of the 40 present application.

Having described my invention, what I claim as new and desire to secure by Letters Patent of the United States is:—

1. A heel machine comprising means for 45 operating upon a heel blank, and mechanism movable from a blank receiving position at one side of the operating means to a position at the opposite side of said means constructed and arranged to engage a blank frictionally, feed it to the operating means, and release it in position to be operated upon by said operating means.

2. A heel machine comprising means for 55 operating upon a heel blank, and a pair of blank edge engaging feed chains at opposite sides of the operating means and extending from a blank receiving position at one side of the operating means to a blank delivering position at the other side thereof.

3. In a heel machine, a compressing mold, and mechanism for feeding a blank to the mold comprising blank edge engaging chains having parallel stretches at opposite sides of the mold.

4. In a heel machine, a compressing mold,

blank edge engaging chains at opposite sides of the mold, means for moving the chains longitudinally to advance blanks placed between them, and means for effecting relative movements of approach and separation between the 70 chains to cause them to engage and disengage said blanks.

5. Mechanism for feeding a plurality of blanks simultaneously to different positions comprising feeding means constructed and arranged to engage all the blanks frictionally and to release all the blanks when one of them reaches one of said positions.

6. Mechanism for feeding a plurality of blanks simultaneously to different positions comprising feeding means for frictionally engaging opposite edges of each blank, and means for releasing the frictional engagement when one of the blanks reaches a predetermined position.

7. A machine for operating upon heel blanks comprising means for performing an operation upon a blank, and single means for feeding a blank in a right line to the operating means, releasing the blank for operation 90 thereon, and transferring the blank away from the operating means after the operation is performed.

8. A heel machine comprising means for operating upon a heel blank, and a pair of feed chains constructed and arranged to engage opposite edges of a blank, feed the blank to the operating means, release the blank for operation thereon, and transfer the blank away from the operating means after the operation is performed.

9. A heel machine comprising means for operating upon a heel blank, and a pair of feed chains constructed and arranged to engage opposite edges of a blank and feed it 105 to and away from the operating means.

10. Blank feeding mechanism comprising feeding members for engaging opposite edges of a blank, a blank support between said feeding members, means for effecting relative movements of approach and separation between said feeding members, and means operating in timed relation to said movements for moving the support into and out of a position in which a blank supported thereon 115 is between the feeding members.

11. In a machine of the class described, the combination of means for operating upon a blank, means for feeding blanks successively through the same distance to the operating means, means for supplying blanks successively to the feeding means, and means for varying the point in the feeding path at which the blank supplying means delivers 120 blanks to the feeding means.

12. In a machine of the class described, the combination of means for operating upon a blank in a plurality of separated positions so located as to require the blank to be fed different distances, a single feeding mecha- 130

- nism engaging the blank frictionally to feed it to the different operating positions and movable intermittently through equal distances, and means for stopping the blank
- 5 at one of the operating positions prior to cessation of movement of the feeding mechanism.
13. In a heel machine, the combination of heel breasting means, and mechanism for
- 10 feeding a blank to the breasting means comprising blank edge engaging chains having parallel stretches at opposite sides of said means.
14. In a heel machine, the combination of
- 15 heel breasting means, blank edge engaging chains at opposite sides of said means, means for moving the chains longitudinally to advance blanks placed between them, and means for effecting relative movements of approach
- 20 and separation between the chains to cause them to engage and disengage said blanks.
15. In a machine for compressing and breasting heels in a continuous operation, means for compressing a heel, means for eject-
- 25 ing the heel from the compressing means, means for breasting the heel, and means for transferring the heel in a single straight line movement from ejected position to breasting position.
- 30 16. In a machine of the class described, the combination of heel compressing means, heel breasting means, and a single mechanism for feeding a heel to the compressing means and transferring it, after compression, from the
- 35 compressing means to the breasting means.
17. In a machine for compressing and breasting heels in a continuous operation, means for compressing a heel, means for
- 40 breasting the heel, a pair of heel edge engaging chains extending from the compressing means to the breasting means, said chains being arranged at opposite sides of both of said means, and means for moving the chains longitudinally to transfer compressed heels
- 45 from the compressing means to the breasting means.
18. A machine for compressing and breasting heels in a continuous operation having separated, alined, heel receiving, heel compressing, and heel breasting stations, and means for feeding heels one at a time from the receiving station to the compressing station and from the compressing station to the breasting station.
- 50 55 In testimony whereof I have signed my name to this specification.

FRED ASHWORTH.
